Primary Examiner—Cathron C. Brooks(74) Attorney, Agent, or Firm—Steinberg & Raskin, P.C.(57) CLAIM

I claim the ornamental design for an article of furniture, as shown and described.

DESCRIPTION

FIG. 1 is a perspective view of the article of furniture;
 FIG. 2 is a front elevational view thereof;
 FIG. 3 is a left side view thereof, the right side being a mirror image thereof; and,
 FIG. 4 is a top plan view thereof.
 The bottom of the article of furniture is flat and unornamented.
 The broken lines are for illustrative purposes only and form no part of the claimed design.
